UNITED STATES PATENT OFFICE.

PAUL BIDAL, OF PARIS, FRANCE.

FASTENING DEVICE FOR LEGGINGS.

Application filed July 21, 1924. Serial No. 727,326.

To all whom it may concern:

Be it known that I, PAUL BIDAL, a citizen of the French Republic, residing at Paris, France, have invented certain new and useful Improvements in Fastening Devices for Leggings, and declare the following to be a full, clear, and exact description of the same, such as will enable others skilled in the art to which it pertains to make and use the same, reference being had to the accompanying drawing, which forms a part of this specification.

My invention relates to devices for firmly fastening or locking together the lower edges of the two overlapping flaps of leggings and the like and has for its object to provide an improved device of this character simple in construction, cheap and easy to manufacture, readily applicable to the legging, of great durability and efficiency in use and rendering it possible to readily engage and disengage the said two flaps by hand whilst absolutely preventing them from disengaging themselves accidentally.

Hitherto, the two overlapping flaps of leggings have been fastened together by different devices such, for instance, as straps attached to buckles or loops, laces passed through a series of eyeleted holes, or else staples, clips, tongues or the like fixedly secured to one flap and engaging similar members on the other flap, or similar devices. However the fastening device most commonly used in the past consists of an upper strap attached to buckles on both flaps of the legging and a steel plate spring retained adjacent the longitudinal edge of the outer flap and engaging a metal socket or similar means secured adjacent the lower end of the inner flap. This fastening device as well as the other ones above referred to has a serious drawback in that it does not provide a rigid locking means for the two overlapping flaps of the legging which can thus disengage themselves during use.

One feature of the present invention consists in providing the inner face of the outer overlapping flap of the legging with the usual fixed steel plate spring which extends adjacent the longitudinal edge of said flap over the greater part of the length thereof but terminates at a short distance from the lower edge of the legging, and in so constructing the said spring that its lower free extremity is reduced in width and tongue-shaped for engagement with a suitably

sized socket fixedly secured to the outer face of the inner flap and having a novel construction as will appear hereinafter. The tongue-shaped extremity of the plate spring is bent lengthwise outwardly, i. e., towards the opposite flap, and is formed centrally at a suitable position intermediate its ends with a hole, preferably circular in shape.

A further feature of the present invention consists in providing the outer face of the inner or underlying flap of the legging with a bridge-shaped socket formed by a small sheet of metal, suitably cut out and bent twice upon itself so as to provide an intermediate flat portion forming, as it were, the platform of the bridge and two perpendicular lugs forming, as it were, its abutments. The said lugs are passed through the leather or other material constituting the said inner flap and bent inwardly over a small securing plate. A counterplate of somewhat larger size than the said plate and having an arcuate upper edge is imprisoned underneath the said bridge on outer face of the flap. The flat intermediate portion or platform of the said bridge is formed centrally with a boss, preferably circular, the diameter of which is slightly smaller than that of the hole formed in the spring above referred to.

For a better understanding of the above-indicated novel features and others which will hereinafter appear, reference may be had to the accompanying drawing exemplifying one embodiment of my invention where-

in:

Figure 1 is a fragmentary elevational view of the inner face of the outer overlapping flap of a legging fitted with the fastening device according to my invention, showing the fixed steel plate spring of novel construction secured thereto.

Figure 2 is a fragmentary edge view of the outer overlapping flap of the legging, showing the angularity of the bent free extremity of the steel plate spring secured thereto.

Figure 3 is a fragmentary elevational view of the outer face of the inner flap of the legging, showing the bridge-shaped socket of novel construction secured thereto.

Figure 4 is a fragmentary sectional longitudinal view of the two overlapping flaps of a legging fitted with the improved fastening device according to my invention.

Figure 5 is a separate isometric view drawn to a larger scale of the bridge-shaped

socket adapted for being secured against the outer face of the underlying flap of the legging.

Like characters of reference designate like parts throughout the several views.

According to the embodiment of my invention illustrated in these figures, the inner face of the outer overlapping flap of the legging generally designated by A is provided with the usual elongated plate spring B, which extends adjacent the longitudinal edge of said flap over the greater part of the length thereof and is secured to the same by means of rivets, eyelets or equivalent fastening means b. The said spring B terminates at a short distance from the lower edge of the legging and its lower free extremity is reduced in width at j and tongue-shaped at k for a purpose which will hereinafter be described. Just where its width begins to taper, the tongue-shaped extremity of the spring B is bent outwardly, i. e., towards the inner flap, so as to form an angle of substantially 20° with the remaining portion of its length which is held applied against the leather of the outer flap. The thus outwardly bent tongue-shaped extremity of the spring B is formed centrally with a hole i, preferably circular in shape. The position of the centre of this hole should preferably be at one third of the length of the said extremity from the line where it begins to taper, as clearly illustrated in the drawing. Moreover, when piercing or punching out this hole with a hand or mechanical tool, care should be taken to cause its edges to flare on both sides for a purpose which will appear hereafter.

The outer face of the inner flap C of the legging is provided at a position corresponding to the lower extremity of the spring B with a bridge-shaped socket. This socket is formed by a small sheet of metal, preferably brass, suitably cut out and bent twice at right angles upon itself, as clearly illustrated in Fig. 5, so as to provide an intermediate flat portion which, so to speak, forms the platform D of the bridge and two perpendicular T-shaped end pieces or lugs G which, so to speak, form the abutments of the bridge. The said lugs are passed through the leather or other suitable supple material constituting the legging and bent inwardly over a small securing plate E, preferably of metal. A counterplate E' of somewhat larger size than the plate E and having an arcuate upper edge E' is imprisoned underneath the said bridge on the outer face of the flap. This counterplate E is formed with two side slots of suitable size for permitting the insertion of the lugs G therethrough when mounting the socket in position on the inner flap. Furthermore, the arcuate edge E' of said counterplate is advantageously depressed against the flap

to a slight extent, as clearly illustrated in Fig. 4, for a purpose to be pointed out hereinafter. The flat intermediate portion or platform D of the bridge-shaped socket is formed centrally with an inwardly projecting boss, preferably circular in shape to match with the hole i formed in the extremity of the spring B and having a diameter slightly smaller than that of the said hole.

The operation of this device will be readily understood from the foregoing description with reference to the figures of the drawing. To fasten or lock together the two overlapping flaps of the legging, all that is necessary is to engage the rounded tip k of the tongue-shaped extremity of the plate spring B secured to the outer flap under the bridged-shaped socket D secured to the inner flap and to sufficiently push by hand (only a comparatively small stress being required) the said spring within the said socket to cause its boss d to register with and penetrate into the corresponding hole i formed in said spring. The introduction of the tip of the said spring into the said socket is facilitated by its flexibility, and the engagement of its hole with the boss formed on said socket is rendered easier by the fact that the edges of said hole are machined or formed according to a slight frusto conical shape, as has been described. Further, the arcuate end edge E' of the counterplate E being depressed, as hereinbefore pointed out, prevents the tip of the spring from engaging and being caught behind said counter-plate whilst directing it outwards and causing it to slide lightly thereupon. Owing to the resiliency of the spring B, when once the boss d has entered the hole i it can not disengage itself so that the two flaps are firmly locked together. If now it is desired to unfasten the said two flaps, this can be performed very easily by the wearer himself. All that is necessary for him is then to press down (by hand) the region of the outer flap adjacent the locking device somewhat to the rear of same whilst simultaneously pulling upward the said outer flap. Owing to the resiliency of the spring and the peculiar form of the hole i formed in the tongue-shaped extremity of said spring, this combined pressure and traction forces the boss formed in the socket out of the hole formed in the said tongue-shaped extremity, whereby the latter may readily be disengaged from the said socket, thus unfastening the two flaps. It will be understood that the sliding motion of tongue into the spring in the socket is greatly facilitated by the provision of the metal counter-plate of peculiar shape on which the tip of the said tongue glides somewhat after the fashion of a skate.

While I have described the preferred construction of fastening device embodying my

invention and the operation thereof, I am aware that certain slight changes of construction or certain omissions of parts may be made without departing from the spirit 5 of the invention as hereinafter claimed.

I claim:—

1. A fastener for connecting overlapping pieces of fabric comprising a member adapted to be secured to one piece of fabric and 10 provided at one end with an outwardly-inclined spring tongue in which an opening is formed; and a companion member adapted to be secured to the other piece of fabric and consisting of a bridge-piece embodying a 15 flat central platform formed with a boss which projects inward from its inner face, and T-shaped ends, a securing plate adapted to be positioned against the inner face of the second-named piece of fabric, and a 20 counterplate adapted to be inserted between said platform and the outer face of said second-named piece of fabric and having slots to enable the stem portions of the ends of the platform to be passed therethrough 25 and through the fabric and bent inward against the face of the counterplate; said tongue adapted to be inserted between the platform of the bridge piece and the counterplate to enable the boss on said platform to snap into engagement in the opening in 30 said tongue.

2. A fastener for leggings, comprising a member provided with an outwardly-inclined spring tongue in which an opening is formed; and a companion member embodying a bridge-piece having end lugs, and a plate adapted to be inserted beneath the bridge-piece and having parallel side slots for the passage of said lugs therethrough, said bridge-piece having a central boss 40 which projects inwardly from its under face toward said plate; said tongue adapted to be inserted between the central portion of the bridge-piece and said plate to enable said boss to snap into engagement in the 45 opening in said tongue.

3. A fastener for leggings, according to claim 2, in which the plate projects upwardly beyond the bridge-piece and is provided with a depressed upper edge to guide 50 the tongue toward the bridge-piece during its insertion beneath the same and to prevent said tongue from catching behind said plate.

4. A fastener for leggings, according to claim 2, in which the plate projects upwardly beyond the bridge-piece and is provided with a bent, arcuate upper edge to guide the tongue toward the bridge-piece during its insertion beneath the same and to prevent 55 said tongue from catching behind said plate. 60

In testimony whereof I affix my signature.
PAUL BIDAL.
